By Attorney

UNITED STATES PATENT OFFICE.

FRANK R. PIPER, OF FAIRFAX, ALABAMA.

ROLLER.

1,416,748.

Specification of Letters Patent. Patented May 23, 1922.

Application filed September 9, 1920, Serial No. 409,284. Renewed January 4, 1922. Serial No. 527,051.

To all whom it may concern:

Be it known that I, FRANK RIDLEY PIPER, a citizen of the United States, residing at Fairfax, in the county of Chambers and 5 State of Alabama, have invented certain new and useful Improvements in Rollers, of which the following is a specification.

My invention relates to improvements in the construction of rollers used in machines 10 for operating upon threads or strands of material during their treatment in a liquid vat.

In the machines in common and general use rollers of wood are employed, and it 15 has been found by long experience that such rollers have a short life, making their use expensive, also that their surface may not wear evenly, also that their use causes a loss of time and delay for adjustment and re- 20 placement, and further that it is a difficult matter to make wood rollers of the proper size and desired surface.

The main object of my invention is the 25 production of a roller which will entirely overcome all of the objections and defects known to exist in the wooden rollers in use, and to provide a roller which will practically last a life time, which will permit the instant application of a contact surface forming a 30 perfect substitute for wood to meet all requirements, which will be of simple and durable construction and capable of production at a comparatively low cost, thus insuring an efficient, desirable and thoroughly practical 35 substitute for the wood roller.

The invention broadly stated consists of a roller consisting of a metal roller or core and a detachable contact surface wound upon and forming a cover around the metal roller. 40 The invention further consists of a roller of the character and for the purposes stated embodying novel features of construction and combination of parts substantially as shown, described and particularly defined 45 by the claims.

In order that the construction in detail and the operation of my invention may be understood and its many features of merit and advantages be fully appreciated, I invite 50 attention to the accompanying drawings in which:

Figure 1 is an end view of twin rollers constructed in accordance with and embodying my invention, showing the relation of 55 the rollers in use,

Figure 2 is a side view of one of the rollers with the helical covering removed,

Figure 3 is a similar view with the helical covering wound upon the body or core of the 60 roller,

Figure 4 is a detail sectional view of one end of the roller, showing the construction of the end heads or caps and the manner of shrinking or threading them on the hollow roller as well as the manner of clamping 65 the ends of the rope or helical covering.

Figure 5 is a detail view of a modification.

The invention is of extremely simple construction and consists of the hollow metal core or body A, the caps or heads B, of some- 70 what larger diameter than the core and formed with a rim C, shrunk or threaded into the ends of the core, and further formed each with a hub D, provided with an opening E, to receive the through shaft F, whose 75 ends project the required distance.

This construction provides a hollow metal roller with flanged caps or heads and upon the roller and confined and retained by the flanged heads is the coiled or helical covering 80 G, preferably of cord or rope of the desired size and material and wound as shown with each end of such helical covering passing through an opening H, at each end of the roller and through the yoke clamps J, which 85 by reason of the nuts K, act to securely fasten the ends L of the helical in place, and also allow the removal of such helical cover when found necessary.

It will thus be seen that my invention 90 provides a substitute for the wood rollers now in use, which will prove a great saving in time, labor and expense; which will permit with ease and facility the application or removal of the contact surface or covering; 95 which will permit the use of various sizes of spiral covering as well as of any suitable material, and which generally will provide a roller construction which will commend itself as thoroughly efficient and practical. 100

The invention may be used for any purpose where it would function properly but is particularly useful, efficient and desirable in cotton mills for cleaning or bleaching the continuous strip of material producing 105 towels and the use of a covering of coiled material such as rope or cord of the proper size is desirable as such a covering exerts the proper pressure or rubbing action against the strip as to effect a much better cleaning 110

of said strip than a roller made of wood, rubber or in fact any other character of material.

I claim:—

- 5 1. A roller for use in textile machines, consisting of a metal core or roller, and a removable covering for said roller, said roller having means for confining and retaining said covering in place.
  - 10 2. A roller for use in textile machines, consisting of a metal roller, and a helically wound covering for said roller, said roller having a flange at each end to confine the covering in proper position.
  - 15 3. A roller for use in textile machines, consisting of a metal core or body, a covering wound around the body, and having its ends free, said roller having means to confine the covering in place, and means for detachably securing the said ends to retain the cover upon said body.
  - 20 4. A roller for use in textile machines, consisting of a metal roller, flanged caps connected to the ends of said roller, and a helical covering wound upon said roller and confined by the flanged caps.
  - 25 5. A roller for use in textile machines, consisting of a metal roller, flanged caps secured to the ends of said roller, a shaft keyed to said caps, a helical covering wound
  - 30
  - 35
  - 40
  - 45
  - 50
  - 55
- upon the entire roller and confined by said flanged caps, and fastenings engaging and retaining the ends of the helical to secure the covering and to allow its removal.
6. A roller for use in textile machines, consisting of a core or body, a covering wound upon said core, and means carried by the core for confining said covering upon the core.
7. A pair of rollers for use in cleaning threads arranged in parallel relation, and a helical covering wound upon said rollers to bear upon the threads and fastenings carried by the rollers for securing the said coverings and permitting removal thereof.
8. A pair of rollers for use in cleaning threads arranged in parallel relation, helical coverings upon said rollers, and flanges on the rollers to confine the coverings in proper place and fastenings carried by the rollers for securing the said coverings and permitting removal thereof.
9. A pair of rollers for use in cleaning threads arranged in parallel relation, and a removable thread engaging covering upon said roller and fastenings carried by the rollers for securing the said coverings and permitting removal thereof.

In testimony whereof I affix my signature.

FRANK R. PIPER.
